PORTABLE SCALE MECHANISM

W Carl Anderson and Sydney L. Dewey, Canton, Ohio, assignors to The Union Metal Manufacturing Company, Canton, Ohio, a corporation of Ohio

Filed Oct. 21, 1953, Ser. No. 387,458

12 Claims. (Cl. 265—40)

The invention relates to scale mechanisms and more particularly to a portable scale mechanism which is especially adapted for use with a lift truck, such as a fork or platform lift truck, for performing a weighing operation during operation of the truck, as by being constructed as a part of the lift truck, or as by being constructed as a separate unit for use as an attachment or an accessory for a lift truck.

Many types and kinds of materials are handled and transported daily in all types, kinds and fields of industry. A great deal of such handling is performed by lift trucks and particularly by fork lift trucks. In many instances, it is necessary to determine the weight of the material handled at some time during handling. Normally, such weighing operation in lift truck materials handling is carried out by transporting the load on the truck to a scale at a fixed location, known as a dormant scale, depositing the load on the scale, weighing the load, and then removing the load from the scale for further desired lift truck handling.

For instance, in the operation of a foundry certain materials are charged to the cupola for melting. Materials handling boxes may be used for accumulating the material to be charged and these boxes normally are handled on a fork lift truck and the contents thereof dumped by the lift truck into the cupola or a cupola charging bin. In such operations, it is necessary to determine quite accurately the weight of the various materials forming a part of the cupola charge. Heretofore, the weighing of materials handled in materials handling boxes and by a fork lift truck for charging a foundry cupola has been a relatively expensive but essentially non-productive operation.

Accordingly, it is a general object of the present invention to provide a scale mechanism which can be associated with a lift truck in such manner that as material or a load to be handled is picked up by the lift truck for transportation, a scale reading can immediately be obtained indicating the weight of the material or load handled, without the necessity of carrying the material on the lift truck to some dormant scale.

This problem is complicated by a number of factors. First, the inherent design of a lift truck for universal use requires that the platform or fork member thereof must have a minimum height or thickness so that the same may be entered into the low clearance space provided on a skid or pallet or box for picking up the latter when free standing on the ground or floor. If it is attempted to use the usual lever mechanism of a platform scale that is provided therein below the platform of a platform scale mechanism and to incorporate the same as a part of the forks or platform of a lift truck, the vertical lift truck platform dimension limitations would be exceeded so that it is impossible, as a practical matter, to enter such a scale platform with scale lever mechanism beneath, into a small fork entry clearance space provided in skid platforms, material handling boxes, pallets, etc.

Second, usual platform scale mechanisms involve the

use of knife edges for the lever suspensions of the scale mechanism. However, such knife edge mountings are impractical for use in a device carried or transported by a lift truck because of their fragile nature and the possibility of damage thereto by the severe abuse to which a lift truck is subjected in normal operation. This abuse may result from uneven surfaces or holes or the like in floors or the ground over which a lift truck may travel, or from quick turning of the lift truck, or from the raising or lowering or the starting or stopping of such raising or lowering of the load on the truck, and from bumping the load during truck manipulation or travel.

Third, if, for space saving, weighing mechanism levers or other devices are to be eliminated from beneath the scale load supporting table or platform, then the load supporting table or platform must be mounted in some manner at one side thereof to suspend it from or otherwise connect it with the weight indicating or recording mechanism and such condition introduces three further problems. The first problem is related to the offset location of the load center on the platform in respect to the side mounting of the platform which tends to tilt or rock the platform with respect to a selected point in the side suspension thereof. The second problem is related to the degree of offsetting of the offset location of the load center with respect to the side mounting of the platform. The third problem is related, viewing the front of the scale platform and looking toward the offset suspension means at the rear thereof, to the lateral offsetting of the load center on the scale platform with respect to a plane passing vertically through the platform centrally from front to rear.

Each of the three last mentioned problems normally can introduce horizontal load components at the point of platform suspension, resulting from the tilting moment imparted to the platform by an offset load center. Any such horizontal load components can affect in varying degree the true vertical load component or dead weight of the load to be transmitted to the weight indicating mechanism.

In other words, the problem is one of applying a load at any position on a cantilever type platform and of obtaining a true indication of the load weight at the weight indicating mechanism from which the platform is suspended, regardless of the location or position of the load center on the platform; and of at the same time providing a platform of minimum thickness, and of providing suspension mechanism therefor which may be subjected to severe abuse in operation on or as a part of a lift truck without introducing errors in the indication of the true weight and without requiring substantial and continuing maintenance and repair to components of the scale mechanism.

We have discovered that these complicated problems may be solved and the indicated difficulties overcome by providing a portable scale mechanism in which an upright standard is provided, which may either be L-shaped to locate means on the horizontal leg thereof for engagement by a lift truck fork or platform, or may be incorporated as a part of the fork or platform carriage of a lift truck; in which a weight indicating mechanism is suspended from the upper end of the upright standard; in which an L-shaped weighing platform member is suspended from the weight indicating mechanism; in which the horizontal leg of the L-shaped weighing platform member forms the load supporting member; in which the vertical leg of the L-shaped weighing platform member is suspended from the weight indicating mechanism closely adjacent the upright standard; and in which parallel and substantially horizontal reacting means are provided at spaced positions both laterally and vertically of the upright standard maintaining the vertical leg member

of the L-shaped weighing platform member against transmitting any vertical components to the weight indicating mechanism from said horizontally reacting means and absorbing in a substantially frictionless manner the horizontal components of tilting forces imparted to the weighing platform by a load applied to the weighing platform offset with respect to the vertical platform leg.

Accordingly, it is a further object of the present invention to provide a scale mechanism in which the usual lever mechanism of a platform scale located below the platform is eliminated and in which scale mechanism knife edge lever suspensions are eliminated.

Furthermore, it is an object of the present invention to provide a new scale mechanism which may be inexpensively fabricated without maintaining close tolerances in the construction and assembly of the scale platform and standard, and which is rugged in construction such that it may be subjected to the severe abuse of operation in conjunction with the normal use of a lift truck under all kinds of conditions and circumstances without affecting the accuracy of weight readings indicated.

Also, it is an object of the present invention to provide a portable scale mechanism having a cantilever type weighing platform suspended from a weight indicating mechanism with means for absorbing horizontal load components imparted to the platform by offset location of a load to be weighed on the weighing platform, so as to give a true load reading at the weight indicating mechanism.

Furthermore, it is an object of the present invention to provide a portable scale mechanism which may be incorporated as a part of the construction of a lift truck, or may be picked up by a lift truck as accessory equipment, for accurately weighing a load picked up or handled by the lift truck; and which is unaffected as to accuracy by the normal abuse to which a lift truck is subjected in usual operation, or by varying atmospheric conditions.

Moreover, it is an object of the present invention to provide a new scale mechanism in which a cantilever type weighing platform is suspended vertically from a weight indicating mechanism, in which means is provided for holding such platform suspended in such manner that only true or actual vertical components of the load are transmitted to the weight indicating mechanism to register an accurate weight indication, and in which a minimum amount of friction, which otherwise might result in horizontal and vertical load components affecting the accuracy of the indicator reading, is developed in said last mentioned means in maintaining the weighing platform in proper suspended position.

Finally, it is an object of the present invention to solve the indicated problems existing in the art, to eliminate the difficulties stated, to generally improve the construction and facility of accurate use of a scale on a lift truck, and to obtain the foregoing advantages and desiderata in a simple and effective manner.

These and other objects and advantages apparent to those skilled in the art from the following description and claims may be obtained, the stated results achieved, and the described difficulties overcome by the constructions, combinations, subcombinations, parts, elements and arrangements which comprise the present invention, the nature of which is set forth in the following general statement, a preferred embodiment of which—illustrative of the best mode in which applicants have contemplated applying the principles—is set forth in the following description and shown in the drawings, and which are more particularly and distinctly pointed out and set forth in the appended claims forming part hereof.

The nature of the improvements in portable scale mechanism of the present invention may be stated in general terms as including an upright standard member, a weight indicating mechanism suspended from the upper end of said upright member, an L-shaped cantilever type weighing platform vertically suspended from said weight

indicating mechanism, horizontally reacting means engaging between the platform member and the upright member absorbing horizontal load components imparted to the platform member by a load applied at any offset position on the horizontal leg of the platform member; and said standard being adapted to be integrated with the fork or platform carriage of a lift truck, or to be mounted on a base to be picked up by the fork or platform of a lift truck.

By way of example, the improved scale construction of the present invention is shown in the accompanying drawings forming part hereof, wherein:

Figure 1 is a perspective view showing the improved portable scale mechanism raised on the fork of a fork lift truck;

Fig. 2 is a perspective view of the portable scale unit shown in Fig. 1;

Fig. 3 is a side elevation of the improved portable scale mechanism illustrated in Figs. 1 and 2;

Fig. 4 is a front elevation of the unit shown in Fig. 3, partly in section taken on the line 4—4, Fig. 3;

Fig. 5 is a rear elevation of the unit shown in Figs. 3 and 4;

Fig. 6 is a fragmentary sectional view taken on the line 6—6, Fig. 4;

Fig. 7 is a top plan view of the unit shown in Figs. 3, 4 and 5 with certain parts removed; and

Fig. 8 is a plan sectional view taken on the line 8—8, Fig. 3.

Similar numerals refer to similar parts throughout the various figures of the drawings.

Although the improved scale mechanism of the present invention is illustrated and described as forming a part of a portable scale, it is to be understood that the improved mechanism also may be incorporated in the construction of dormant scales.

Furthermore, the improved scale mechanism for convenience is illustrated in the drawings as incorporated in a portable scale attachment or accessory for a fork lift truck, but it is to be understood that the same also may be incorporated directly as a part of the fork carriage of a fork lift truck.

A fork lift truck is indicated generally at 1 handling a scale unit generally indicated at 2 incorporating the improved scale mechanism of the present invention, the unit 2 being constructed for use as an attachment or accessory for a fork lift truck.

The fork lift truck 1 may include the usual wheels 3 and mast 4 on which the fork carriage is mounted for raising and lowering usual fork members 5. The lift truck mast 4 and fork members 5 are illustrated in dot-dash lines in Fig. 3, and the fork members 5 are illustrated in dot-dash lines in Fig. 4.

Referring particularly to Figs. 2, 3 and 4, the improved portable scale unit 2 includes an upright standard member generally indicated at 6 and an L-shaped cantilever type weighing platform member generally indicated at 7. When the scale unit is constructed as a portable scale unit for a fork lift truck, the standard member 6 is also preferably L-shaped as shown in the drawings. A weight indicating mechanism generally indicated at 8 is suspended from the standard member 6 and, in turn, suspends the platform member 7 in a manner to be described in detail below.

The standard member 6, as shown, includes an upright leg 9 and a base leg 10, and the upright leg 9 is formed of spaced upright channel members 11 connected at the top by an angle member 12 and intermediate their ends by a channel member 13 and with front and rear plates 14 and 15 forming a box-like frame in cross-section, the parts 11, 12, 13, 14 and 15 being metal and welded together in a usual manner.

The base leg 10 of the standard member 6 is also preferably formed by spaced channel members 16 and

upper and lower plate members 17 and 18 also forming a box-like shape in cross-section (Fig. 4).

The standard upright leg 9 and base leg 10 are preferably joined by a mitered joint which may include an angularly located plate 19 welded to the lower ends of plate members 14 and 15 and channel members 11, and also welded to the rear ends of plate members 17 and 18 and channel members 16 to form a stiff and strong angular joint at the base of the standard member 6. If desired, the rear plate member 15 may be bent at its bottom corner and formed as a continuation of the bottom plate member 18. Similarly, the front plate 14 may be bent at its lower end and formed as a continuation of upper plate 17. The front ends of the spaced channel members 16 preferably are cut off at an angle and the bottom plate member 18 may extend upwardly, as indicated at 20 covering the front ends of channel members 16. When the unit is free standing, the bottom plate 18 of the base leg 10 rests on the floor indicated by the floor line 21.

Two spaced channel members 22 and 23 are mounted on the top plate 17 of the base leg 10 and project laterally from the top of the base leg 10 in an outrigger-like manner, the projecting undersides of channel members 22 and 23 preferably being closed by plate members 24 forming fork engaging means, underneath which the fork members 5 of a fork lift truck may be projected so as to engage members 22 and 23 (Figs. 3 and 4) for lifting the standard member 6 on the fork lift truck as shown in Fig. 1.

The outrigger fork engaging means may be supplemented by laterally projecting angle members 25 which extend laterally outwardly near the lower corner of the upright standard 6 from the channel members 12 thereof and these members 25 also protect the platform member 7. Another angle member 26 may be secured to angle members 25 and the rear plate 15 by knee braces 27 to form a rearward abutment for properly locating the scale unit 2 with respect to the truck mast 4 when the scale unit 2 is being handled by the fork lift truck 1 (Fig. 3). The upright leg of the angle member 26 may, if desired, be engaged by a movable member 28 (Fig. 3) on the mast 4 for holding the scale unit 2 on the fork carriage when the fork carriage and scale are being withdrawn from underneath a skid platform or the like being handled by the lift truck. A projecting plate 29 also may be provided, mounted with knee braces 30 on rear plate 15, if desired, to properly locate the scale unit 2 with respect to lift truck member 28 when locking the scale unit 2 to the lift truck.

A yoke member 31 is mounted centrally at the upper end of the standard member 6 projecting forwardly from angle member 12, and a pivot pin 32 is mounted in yoke member 31 from which the weight indicating mechanism 8 is suspended by an ear 33, the pivot joint between ear 33 and pivot pin 32 being loose and universally flexible.

The platform member 7, as indicated, is L-shaped and cantilever-like and preferably includes laterally spaced upright leg portions 34, and laterally spaced horizontal fork-like weight receiving leg portions 35. Each of leg portions 34 and 35 may be box-like in cross-section, as shown; and leg portions 34 and 35 are joined by a mitered joint 36. The front ends of horizontal leg portions 35 may be connected by a box-like front member 37 holding the fork-like leg portions 35 spaced apart at a location generally above the location of the forks 5 of the lift truck (Fig. 4).

As best shown in Figs. 6 and 8, the laterally spaced upright leg portions 34 of the platform member 7 are located laterally adjacent the upright leg 9 of the standard member 6. The upper ends of the upright leg portions 34 are connected by a front cross plate member 38 which forms a saddle-like arrangement in cross-section, with leg portions 34 (Fig. 6), so that the plate 38 straddles the standard member upright leg 9.

Spaced bosses 39 are mounted on the upper edge of cross plate 38, adjacent cutout portion 40, and a pivot pin 41 is journaled in bosses 39. The pivot pin 41 is pivotally connected with a suspension member 42 of the weight indicating mechanism 8, the pivot joint between members 41 and 42 being loose and universally flexible.

The weight indicating mechanism 8 may be formed of any usual construction preferably having a dial scale 43 with a pointer 44 actuated to indicate a weight reading by deflection or movement of the suspending member 42. Although the deflection of the suspending member 42 in various types of weight indicating mechanisms on the market, when the mechanism is loaded, may be small or considerable, it is preferred in accordance with the present invention to have the deflection of member 42 as small as possible such as a few thousandths of an inch, say .020" for example, although it is to be understood that this deflection may be larger depending upon the particular type of weight indicating mechanism utilized.

20 In accordance with the present invention, a channel member 45 is mounted at the upper end of each upright leg portion 34 of the platform member 7 projecting forwardly outwardly, and a block 46 is mounted at the top of the forward end of each member 45. A U-shaped bracket 47 is mounted at each side of the upright leg 9 of standard member 6 adjacent each block 46 (Fig. 3) and a chain-link 48 is connected between the bracket 47 and block 46 by a pivot pin 49 and an eye member 50, the location of the eye 50 with respect to block 46 being adjustable by nuts 51 threaded onto the end of eye member 50.

35 The chain-link 48 thus forms a chain-link means universally flexible in all planes connecting the upper ends of the standard and platform members 6 and 7 together; and the pivot joints at the ends of the chain-link means 48 in accordance with the invention are loose and universally flexible.

40 Viewing Figs. 3, 4 and 7, the chain-link means 48 constitute a pair of spaced, parallel, upper, horizontally reacting chain-link connections between the upper ends of the standard and platform members.

45 Referring particularly to Figs. 2, 3 and 8, a channel member 52 is connected laterally between the rear ends of the platform member leg portions 35; and the forward flange of member 52 is cut out at spaced regions as indicated at 53. U-shaped brackets 54 are mounted within the channel 52 on the rear leg thereof opposite the cut-out portions 53. Likewise, a block 55 is mounted on the channel member 22 on standard member 6 forwardly of each bracket 54 (Fig. 8); and a chain-link 56 is connected between each bracket 54 and its corresponding block 55 by a pivot pin 57 and an eye member 58, the location of the eye 58 with respect to block 55 being adjustable by nuts 59 threaded onto the end of eye members 58.

50 The chain-link 56 thus forms a chain-link means universally flexible in all planes connecting the lower ends of the standard and platform members 6 and 7 together; and the pivot joints at the ends of the chain-link means 56 in accordance with the invention are loose and universally flexible.

55 Viewing Figs. 3, 4 and 7, the chain-link means 56 constitute a pair of spaced parallel, lower, horizontally reacting chain-link connections between the lower ends of the standard and platform members; and the two pairs of chain-link means 48 and 56 constitute spaced pairs of parallel upper and lower horizontally reacting chain-link means connected between the platform and standard members.

60 Referring to Figs. 5 and 6, a lug or boss 60 is mounted on and projects rearwardly from the front cross plate member 38 at the top end of the platform member 7; and two spaced U-shaped brackets 61 are mounted on the upright channel members 11 of standard member 6, laterally opposite the lug 60. The center link 62 of

chain-link 63 (Fig. 6) is welded to lug 69 and the ends of chain-link 63 are connected by pivot pins 64 to brackets 61.

The chain-link 63 thus forms a chain-link means universally flexible in all planes laterally connecting the upper ends of the standard and platform members 6 and 7 together; and the pivot joints at the ends of the chain-link means 63 in accordance with the invention are loose and universally flexible.

Referring to Figs. 2, 4, 7 and 8, a lug or boss 65 is mounted centrally on the upper plate member 17 of the base leg 10 of standard member 6 and U-shaped brackets 66 are mounted on and project inwardly from the inside of platform member leg portions 35 laterally opposite lug 65. The center link 67 of chain-link 68 is welded to lug 65 and the ends of chain-link 68 are connected by pivot pins 69 with brackets 66.

The chain-link 68 thus forms a chain-link means universally flexible in all planes laterally connecting the lower ends of the standard and platform members 6 and 7 together; and the pivot joints at the ends of the chain-link means 68 in accordance with the invention are loose and universally flexible.

The chain-link means 63 and 68 constitute spaced upper and lower, laterally extending, horizontally reacting chain-link connections between the upper and lower ends of the standard and platform members.

Furthermore, the chain-link means 48 and 56 which extend fore and aft of the scale unit, and the laterally extending chain-link means 63 and 68 restrain and hold platform member 7 in the desired position suspended from the weight indicating mechanism 8 and absorb horizontal components of tilting forces imparted to the platform member by a load applied at any offset position on the weight receiving leg portions 35 of the platform member.

All of the chain-link means 48, 56, 63 and 68 when subjected to load act as tension members, the chain-link means 48 and 56 being in tension at all times even when the scale unit 2 is free standing because of the inherent tilting moment imparted thereto by the cantilever construction thereof suspended from the weight indicating mechanism 8 at the top of the upright leg portions 34 thereof.

If desired, stop or guide lugs 70 may be mounted on standard member channel 23 slightly spaced from and just inside of the leg portions 35 of the platform member 7 to stop twisting movement of the platform member incident to bumping the front end or corners of the platform leg portions 35 into some fixed object when the scale unit 2 is being manipulated on the lift truck 1 or entered under a skid platform or the like.

One of the important aspects of the present invention is the vertical suspension of a cantilever type or L-shaped weighing platform from a weight indicating mechanism, which in turn is suspended from the upright standard member of the scale. This vertical suspension will transmit all vertical load components to the weight indicating mechanism. Any turning moments resulting from applying the load to the weighing platform offset with respect to the vertical suspension are absorbed by the horizontal parallel linkage connections between the weighing platform and the upright standard.

That is to say, the upper laterally spaced pair of chain-links connecting the weighing platform and standard member extend in a fore and aft direction, looking from the front of the platform toward the rear or upright leg member thereof; and these chain-links likewise extend horizontally and parallel with each other and parallel with the similarly disposed laterally spaced lower pair of horizontally extending chain-links connected between the platform and standard members.

These chains are structurally speaking, links, and form a parallel horizontally extending linkage system such that any turning moment to which the weighing platform is subjected, due to the position of a load or load center on the platform, results in equal and opposing horizontal

load components through the upper and lower spaced pairs of parallel horizontally extending chain-links. These horizontal components cancel each other and the load transmitted to the weight indicating mechanism represents only the vertical component of the applied load and therefore gives a true load reading at the weight indicating mechanism.

Any friction at the pivot joints of any such linkage system can introduce an error in the reading. In conventional platform lever scales, such friction is minimized by the provision of knife edges at bearing points. However, knife edge constructions are too fragile for practical use in connection with the operation of a lift truck.

The elimination of friction at the pivot joints of the described linkage system can be accomplished by providing for complete flexibility of the links in all planes, and by providing looseness at the link pivot joints. This is achieved in accordance with the embodiment of the invention disclosed by the use of chains for the links, which chains have flexibility in all directions and loose pivot joints.

Another important aspect of the invention related to the parallel, loosely pivoted, flexible linkage system arrangement and necessary for obtaining errorless readings, is the provision of a weight indicating mechanism having a suspending member, which actuates the indicator and from which the weighing platform is suspended, that moves only a small distance vertically from no load to full load condition.

In other words, the deflection from no load to full load of the weight indicating mechanism suspending member should be of the order of a few thousandths of an inch, up to about 0.020". By providing such small deflection for the suspending member, the deviation of the link end pivot joints from the horizontal when a load is applied to the weighing platform is so small, as compared to the lengths of the links, that vertical components possibly present at the link pivot joints are negligible. The amount of deviation of the link support points during weighing may affect the accuracy of the scale system; and if there is a large deflection of the suspending member, the deviation of the link support points from the horizontal would be large, and would introduce vertical components at the link pivot points, resulting in substantial error in the weight indicating readings.

Thus, as a load is picked up and supported by the weighing platform, there is relatively small downward travel of the weighing platform with respect to the upright standard because of the slight deflection of the suspending member. When a lift truck is operated and a load picked up, the entire scale mechanism may be shaken down, so to speak, by truck or fork carriage movement, and the scale mechanism parts assume a static position. Any vertical components due to friction between the chain links and the pivot connections at the ends of the links are so small as to be negligible.

Moreover, if the scale or truck is used for instance in connection with foundry operations where grit, sand, dust or other foreign material may be present and can collect on the parts of the scale mechanism, such foreign material is loosened from and drops from the link pivot joints during the "shake down" of the scale mechanism, because of the looseness of the joints. Thus, the improved construction eliminates the development of friction at the linkage pivot points from foreign material.

Although spaced upper and lower pairs of horizontal parallel chain-link-means are illustrated in the embodiment of the invention shown in the drawings, the result accomplished by the same may also be obtained by the substitution of a single chain-link-means for either the upper, or the lower, or both the upper and lower pairs of chain-link-means; namely, the equalization or cancelling of opposed horizontal load components transmitted to the links from turning moment due to offset positioning of the load on the weighing platform. If one chain-link-

means is used in place of two at either location, the same should be centrally located and all chain-link-means provided must be parallel and substantially horizontal. However, it is preferred to use spaced upper and lower pairs of parallel chain-link-means in order to provide a more rugged and stable construction.

Although the fore and aft upper and lower pairs of spaced parallel chain-link-means have been illustrated and described as being located horizontal, and although such horizontal location is preferred, these chain-link-means need not necessarily be horizontal as long as they are parallel.

Since the described upper and lower chain-links that extend fore and aft with respect to the weighing platform, viewing the front thereof, are chains and are flexible in all planes, they have no lateral stability. Thus a load placed on the weighing platform laterally to one side or the other of a vertical plane passing centrally from front to rear through the weighing platform will tend to cause a lateral swing of the weighing platform. Such lateral swing or tilting is eliminated by the upper and lower horizontal laterally extending chain-links connected between the weighing platform and the standard member. These lateral chain-links function in a manner similar to the upper and lower pairs of chain-links, herein sometimes termed fore-and-aft extending chain links, in that they transmit any lateral horizontal components, resulting from lateral swinging or tilting of the platform by a laterally offset applied load, to the standard member and cancel each other. Thus the lateral chain-links do not accept any vertical components resulting from lateral tilting moments for transmission to the weight indicating mechanism.

In the construction shown in the drawings, the upper lateral chain-link-means is centrally attached to the weighing platform and pivoted at its ends through clevis connections with the standard member; while the lower lateral chain-link-means is connected centrally to the standard member and at its ends through clevis connections with the weighing platform. In either instance, the center and end connections of the lateral chain-link-means may be reversed; or separate chain-link connections may extend laterally in each direction at each location rather than attaching a center link of a chain to one of the members.

Another reason for using a minimum load deflection of the suspending member of the weight indicating mechanism is that with a long travel for such member, the lateral chain-link connections between the weighing platform and standard will tend to tighten the laterally extending portions thereof in both directions, which might result in the transmission of improper vertical load components to the weight indicating mechanism.

Accordingly, another important aspect of the present invention is that the lateral chain-link connections are loose enough that no vertical components are transmitted through the same throughout the deflection or movement of the weight indicating mechanism suspending member. This looseness condition is not present with respect to the fore and aft extending chain-link-means when the device is in no load condition, because of the cantilever character of the weighing platform. Thus, the tare weight of the weighing platform, the load center of which is offset from the point of suspension thereof from the weight indicating mechanism, constantly subjects the platform to a turning moment. This turning moment is resisted by the tightening of the upper and lower fore and aft extending chain-links which establish the static location of the weighing platform with respect to the standard, and as suspended by the weight indicating mechanism.

Because of this condition, it is preferred in the original assembly of the improved scale mechanism, that the upright leg of the weighing platform be located as nearly

in vertical position as possible, with the upper end lower fore and aft extending chain-link-means parallel and as nearly horizontally extending as is possible. This matter can be readily taken care of by the adjusting means provided for the fore and aft chain-link-means.

It is desirable from another standpoint that the upright leg of the weighing platform extend vertically upward rather than being angled, as assembled. If the upright leg extends vertically rather than at an angle, it may be located at a minimum distance from the fork carriage when the scale mechanism is picked up by a lift truck. By keeping such distance a minimum, the load center of the load being handled may be located at a minimum distance from the fork carriage. The further that the load center is from the front of the front lift truck wheels, the greater is the possibility of turning the truck over forwardly on its nose by an attempt to pick up an overload.

Another important aspect of the invention is that the suspension of the weight indicating mechanism from the upright standard member, and the suspension of the weighing platform from the weight indicating mechanism should comprise pivot joints loose in every direction, in the same manner that similar loose pivot joints are provided for each chain-link pivot. In every instance, the degree of looseness should be such that foreign matter will shake or drop out of the pivot connections when the load is shaken down for weighing.

Another desirable aspect of the present invention is that all chain-link members operate as tension members when under load, rather than as compression members, which minimizes the possibility of trouble or errors due to friction. Thus, if these link means were compression rather than tension members, no matter how much care may be exercised in providing anti-friction joints for the pivot points thereof, "Brimmelling" of the relatively rotatable pivot joint surfaces under compression can occur during use which may result in increased friction at the joints causing friction-originated vertical components to be transmitted to the weight indicating mechanism and giving an inaccurate load reading.

Accordingly, the present invention provides a new scale mechanism for accurately weighing a load applied at any offset position on the platform of a cantilever type scale platform suspended from one side thereof; provides a weighing mechanism of the character indicated which is actuated only by vertical load components; provides a new vertical suspension scale construction; provides a mechanism which may be utilized as a part of a portable scale with a lift truck either as a part of or as an accessory for the lift truck; provides a lift truck scale mechanism from which a weight reading can be obtained at any time that a load is carried by the lift mechanism of the truck; provides an improved scale mechanism construction in which the scale platform or table may be constructed to have a minimum height or thickness; provides a scale mechanism in which knife edge mounted lever suspensions or pivot points are eliminated; provides a scale construction which is very rugged in construction and can be operated under all kinds of conditions and subjected to severe abuse without causing any damage to the mechanism or inaccuracies in weight readings; provides a scale mechanism which does not require substantial or constant maintenance or repair to insure accurate weight readings; provides a construction including parallel and substantially horizontal reacting means between the scale standard and weighing platform to absorb in a substantially frictionless manner horizontal components of tilting forces imparted to the weighing platform by a load applied to the weighing platform offset from the suspension of the platform from the weight indicating mechanism; provides a new scale construction which may be inexpensively built; provides a scale construction which solves long standing problems in the

art, eliminates the difficulties stated and which is accurate in use and obtains the foregoing advantages and desiderata in a simple and effective manner.

In the foregoing description, certain terms have been used for brevity, clearness and understanding; but no unnecessary limitations are to be implied therefrom beyond the requirements of the prior art, because such terms are utilized for descriptive purposes herein and not for the purpose of limitation, and are intended to be broadly construed.

Moreover, the description of the improvements is by way of example, and the scope of the present invention is not limited to the exact details illustrated or to the specific size and shape shown.

Having now described the features, discoveries and principles of the invention, the construction and use of the improved scale mechanism, the characteristics thereof, and the advantageous new and useful results obtained thereby; the new and useful constructions, combinations, subcombinations, parts, elements, arrangements, discoveries and principles, and mechanical equivalents obvious to those skilled in the art are set forth, in the appended claims.

We claim:

1. Portable scale mechanism adapted to be used as an attachment for a fork lift truck including an L-shaped upright standard member, the standard member including an upright leg and a base leg, there being outrigger fork engaging means projecting laterally from the top of the base leg, a weight indicating mechanism suspended centrally from the upper end of the upright leg, an L-shaped cantilever type weighing platform member centrally suspended from said weight indicating mechanism, said platform member having laterally spaced upright leg portions laterally adjacent said upright leg and having laterally spaced horizontal fork-like weight receiving leg portions above said fork engaging means, spaced parallel upper horizontally reacting chain-links connected between the upper end of the standard upright leg and the upper ends of the platform upright leg portions by pivot joints, spaced parallel lower horizontally reacting chain-links connected between the base leg and weight receiving leg portions by pivot joints, an upper laterally extending chain-link having a central link fixed centrally to the upper end of the platform member and having its ends connected with the upper end of said upright leg by pivot joints, a lower laterally extending chain-link having a central link fixed centrally to said base leg and having its ends connected to the platform leg portions by pivot joints, said lower parallel chain-links and said lower laterally extending chain-link being located in the space between said laterally spaced platform leg portions, and each of said pivot joints being loose and universally flexible.

2. The construction defined in claim 1 in which adjustable means is provided for certain pivot joints of said upper and lower parallel chain-link means.

3. Scale mechanism including an upright standard member, a weight indicating mechanism suspended centrally from the upper end of the standard member, an L-shaped cantilever type weighing platform member centrally suspended from said weight indicating mechanism, said platform member having laterally spaced upright leg portions laterally adjacent said standard member and having laterally spaced horizontal fork-like weight receiving leg portions, spaced parallel upper horizontally reacting chain-links connected between the upper end of the standard member and the upper ends of the platform upright leg portions by pivot joints, spaced parallel lower horizontally reacting chain-links connected between the standard member and weight receiving leg portions by pivot joints, an upper laterally extending chain-link having a central link fixed centrally to the upper end of the platform member and having its ends connected with the upper end of said standard member by pivot joints, a

lower laterally extending chain-link having a central link fixed centrally to said standard member and having its ends connected to the platform leg portions by pivot joints, said lower parallel chain-links and said lower laterally extending chain-link being located in the space between said laterally spaced platform leg portions, and each of said pivot joints being loose and universally flexible.

4. Fork lift truck scale mechanism including a lift mast, a fork carriage vertically movable on the mast, an upright standard member carried by the carriage, a weight-indicating mechanism mounted on the standard member, an L-shaped cantilever type weighing platform member having an upright leg and a horizontally extending weight receiving leg, means universally flexibly pivotally vertically suspending the platform member from the weight-indicating mechanism, horizontally reacting means engaging between the platform and standard members holding said platform member suspended in such manner that only actual vertical components of a load applied to the platform member are transmitted to the weight-indicating mechanism to register an accurate weight indication thereon, said reacting means being flexible in substantially all directions other than in tension including at least limited twisting, and at least certain of said reacting means engaging between the platform member weight receiving leg and the standard member and extending totally forwardly of said platform member upright leg for providing maximum stability between the platform and standard members.

5. Scale mechanism including an upright standard member, a weight-indicating mechanism suspended from the upper end of said standard member, an L-shaped cantilever type weighing platform member suspended from said weight-indicating mechanism, said weighing platform member having an upright leg and a horizontally extending weight receiving leg; spaced, parallel, upper and lower, fore and aft extending, horizontally reacting, chain-link, tension means connected between the platform and standard members substantially frictionlessly absorbing horizontal load components imparted to the platform member by a load applied at any offset position on the horizontal leg of the platform member; said chain-link tension means being flexible in substantially all directions other than in tension including at least limited twisting, and at least certain of said chain-link tension means being connected between the platform member weight receiving leg and the standard member and extending totally forwardly of the platform member upright leg for providing maximum stability between said standard member and platform member.

6. Scale mechanism including an upright standard member, a weight-indicating mechanism suspended from the upper end of said standard member, an L-shaped cantilever type weighing platform member suspended from said weight-indicating mechanism, said platform member having an upright leg and a horizontally extending weight receiving leg, spaced upper and lower pairs of fore and aft extending parallel substantially horizontal chain-links connected between the platform and standard members, spaced upper and lower laterally extending chain-links connected between the platform and standard members, said chain-links being flexible in substantially all directions other than in tension including at least limited twisting, at least certain of said fore and aft and at least certain of said laterally extending chain-links being connected between the platform member weight receiving leg and the standard member and extending totally forwardly of the platform member upright leg, and said chain-links substantially frictionlessly absorbing horizontal load components imparted to the platform member by a load applied at any offset position on the horizontal leg of the platform member.

7. Scale mechanism including an upright standard member, a weight indicating mechanism suspended from

the upper end of said standard member, an L-shaped cantilever type weighing platform member suspended from said weight indicating mechanism and having a horizontal leg, spaced parallel upper and lower horizontally reacting chain-link means connected between the platform and standard members, spaced upper and lower laterally reacting flexible means connected between the platform and standard members for resisting substantially all lateral movement of the platform member on the standard member while being substantially frictionlessly flexible with respect to limited vertical movement therebetween, said chain-link means and flexible means substantially frictionlessly absorbing horizontal load components imparted to the platform member by a load applied at any offset position on the horizontal leg of the platform member, and said chain-link means and flexible means being flexible in substantially all directions other than in tension including at least limited twisting.

8. Scale mechanism including an upright standard member, a weight indicating mechanism suspended from the upper end of said standard member, an L-shaped cantilever type weighing platform member extending from said weight indicating mechanism and having a horizontal leg, spaced parallel and lower horizontally reacting tension link means connected between the platform and standard members, spaced upper and lower laterally reacting flexible means connected between the platform and standard members for resisting substantially all lateral movement of the platform member on the standard member while being substantially frictionlessly flexible with respect to limited vertical movement therebetween, said tension link means and flexible means substantially frictionlessly absorbing horizontal load components imparted to the platform member by a load applied at any offset position on the horizontal leg of the platform member, and said tension link means and flexible means being flexible in substantially all directions other than in tension including at least limited twisting.

9. Scale mechanism including an upright standard member, a weight indicating mechanism suspended from the upper end of said standard member, an L-shaped cantilever type weighing platform member suspended from said weight indicating mechanism and having a horizontal leg; spaced, parallel, upper and lower, fore and aft extending, horizontally reacting, chain-link, tension means connected between the platform and standard members; spaced upper and lower laterally reacting flexible means connected between the platform and standard members for resisting substantially all lateral movement of the platform member on the standard member while being substantially frictionlessly flexible with respect to limited vertical movement therebetween, said chain-link tension means and flexible means substantially frictionlessly absorbing horizontal load components imparted to the platform member by a load applied at any offset position on the horizontal leg of the platform member, and said chain-link tension means and flexible means being flexible in substantially all directions other than in tension including at least limited twisting.

10. Scale mechanism including an upright standard member, a weight indicating mechanism suspended from the upper end of said standard member, an L-shaped cantilever type weighing platform member suspended from said weight indicating mechanism and having a horizontal leg, spaced parallel upper and lower horizontally

reacting chain-link means connected between the platform and standard members, spaced upper and lower laterally extending chain-link means connected between the platform and standard members, said horizontally reacting and laterally extending chain-link means being flexible in substantially all directions other than in tension including at least limited twisting, and said horizontally reacting and laterally extending chain-link means substantially frictionlessly absorbing horizontal load components imparted to the platform member by a load applied at any offset position on the horizontal leg of the platform member.

11. Scale mechanism including an upright standard member, a weight indicating mechanism suspended from the upper end of said standard member, an L-shaped cantilever type weighing platform member suspended from said weight indicating mechanism and having a horizontal leg, spaced upper and lower pairs of fore and aft extending parallel substantially horizontal chain-links connected between the platform and standard members, spaced upper and lower laterally extending chain-links connected between the platform and standard members, said chain-links being flexible in substantially all directions other than in tension including at least limited twisting, and said chain-links substantially frictionlessly absorbing horizontal load components imparted to the platform member by a load applied at any offset position on the horizontal leg of the platform member.

12. Scale mechanism including an upright standard member, a weight indicating mechanism suspended from the upper end of said standard member, an L-shaped cantilever type weighing platform member suspended from said weight indicating mechanism, said platform member having an upright leg and a horizontally extending weight receiving leg, said upright leg being generally saddle-shaped in cross-section and laterally straddling said upright standard member, spaced parallel upper and lower horizontally reacting means engaged between the platform and standard members substantially frictionlessly absorbing horizontal load components imparted to the platform member by a load applied at any offset position on the weight receiving leg of the platform member, and said reacting means being flexible in substantially all directions other than in tension including at least limited twisting.
